United States Patent [19]

Brown

[11] Patent Number: Des. 311,345

[45] Date of Patent: ** Oct. 16, 1990

[54] DIGITAL CIRCUIT BOARD TESTER

[75] Inventor: Jeffrey C. Brown, Seattle, Wash.

[73] Assignee: John Fluke Mfg. Co., Inc., Everett, Wash.

[**] Term: 14 Years

[21] Appl. No.: 122,653

[22] Filed: Nov. 13, 1987

[52] U.S. Cl. D10/78

[58] Field of Search D10/75-80;

[57] CLAIM

The ornamental design for a digital circuit board tester, as shown and described.

DESCRIPTION

FIG. 1 is a top plan view of a digital circuit board tester showing my new design;
FIG. 2 is a front elevational view;
FIG. 3 is a right side elevational view;
FIG. 4 is a left side elevational view;
FIG. 5 is a rear elevational view;
FIG. 6 is a bottom plan view; and
FIG. 7 is a top, front, and left side perspective view thereof.
